US00D841937S

(12) **United States Design Patent** (10) Patent No.: **US D841,937 S**
(45) Date of Patent: **** Mar. 5, 2019**

(54) **GARMENT**

(71) Applicant: **adidas AG**, Herzogenaurach (DE)
(72) Inventors: **Deborah Yeomans**, Herzogenaurach (DE); **Andreas Metzger**, Herzogenaurach (DE); **Bettina Weiss**, Herzogenaurach (DE); **Roger Hahn**, Herzogenaurach (DE)

(73) Assignee: **adidas AG**, Herzogenaurach (DE)

(**) Term: **15 Years**

(21) Appl. No.: **29/626,792**

(22) Filed: **Nov. 20, 2017**

Related U.S. Application Data

(63) Continuation of application No. 29/565,603, filed on May 23, 2016, now Pat. No. Des. 809,245.

Foreign Application Priority Data

Nov. 27, 2015 (EM) 002879551

(51) LOC (11) Cl. **02-02**

(52) U.S. Cl.

USPC **D2/731**

Field of Classification Search

USPC D2/731, 712-714, 728, 732-734, 738, D2/742-743; 2/456-458, 2.15, 2.16, 67, 2/82

CPC A62B 17/001; A41B 11/00; A41D 7/00; A41D 1/06; A41D 1/08; A41D 13/02; A41D 13/0007; A41D 13/012; A41D 2400/24; A41D 15/00; B63C 9/087; B63C 11/04

See application file for complete search history.

CLAIM

The ornamental design for a garment, as shown and described.

DESCRIPTION

FIG. 1 is a front view of a garment;

FIG. 2 is a rear view of the garment of FIG. 1;

FIG. 3 is a right side view of the garment of FIG. 1, it being understood that the left side is a mirror image of the right side view;

FIG. 4 is a top view of the garment of FIG. 1; and,

FIG. 5 is a bottom view of the garment of FIG. 1.

The dashed broken lines in the drawings depict environmental subject matter that forms no part of the claim. The dash-dot-dash broken lines define the boundaries of the claim that form no part of the claim.

1 Claim, 5 Drawing Sheets

FIG. 1

FIG. 2

FIG. 3

FIG. 4

FIG. 5
